UNITED STATES PATENT OFFICE.

FELIX STERNTHAL, OF CHICAGO, ILLINOIS.

SILVERWARE CONTAINER.

Application filed May 25, 1926. Serial No. 111,553.

My invention relates to a silverware container and the same has for its main object to provide an article of this character which will embody certain desired features of simplicity, efficiency and convenience, and which will be economical in manufacture.

Another object of my invention is to provide a silverware container capable of being folded up into a neat, attractive and compact form and capable also, when spread out, of effectively displaying the articles of silverware arranged therein.

Another object of my invention is to provide a container having the characteristic of a book-fold in that one section or part is foldable over and upon another section or part, prior to the final folding of the structure into compact form; each of the sections or parts being furnished with means for carrying a number of pieces of silverware.

A still further object of my invention is to provide in a container having the foregoing features, a series of pockets of different extent to accommodate different sizes of silverware, all of the pockets being open on an even line facing the folding line of the book-fold.

Other objects will appear hereinafter.

The invention consists in the combinations and arrangements of parts hereinafter described and claimed.

The invention will be best understood by reference to the accompanying drawings forming a part of this specification, and in which,

Fig. 1 represents a plan view of my improved container as it appears when spread out, this view showing the interior side of the container;

Fig. 2 is a perspective view showing how the book-folded sections may be transversely folded into compact form;

Fig. 3 represents another plan view of the container as it appears when spread out, this view showing the exterior side of the container;

Fig. 4 represents a cross section on an enlarged scale, this view being taken on the line 4—4 of Fig. 1;

Fig. 5 represents an enlarged section taken on the line 5—5 of Fig. 1; and,

Fig. 6 is an enlarged detail section taken on the line 6—6 of Fig. 1.

In the accompanying drawings, which illustrate the preferred embodiment of my improved silverware container, 7 designates

a backing sheet made of any pliable material suitable for use as an outside cover, and 8 designates a coextensive wrapping sheet made of flannel or other pliable material commonly employed in wrapping silverware. The coextensive sheets 7 and 8 are secured together along their marginal edges by means of a suitable binding strip 9 and a line of stitching 10.

One of the objects of the present invention is to produce a container having the character of a book-fold; and to this end the connected pliable sheets 7 and 8 are folded over and upon each other along a central folding line 11 so as to produce right and left-hand sections 12 and 13. The pliable sheets 7 and 8 at the end of one section, herein shown to be section 12, are formed with corresponding extensions to produce a flap 14, said extensions being bound along the marginal edge by a binding strip 15 comprising a continuation of the binding strip 9.

Associated with the wrapping sheet 8 on each section 12 and 13 is a series of transverse pockets 16 which extend inwardly of the wrapping sheet from the outer free edge of the section and which open on a line 17 parallel with and spaced a distance from the folding line 11. Each series of pockets 18 is produced by securing a pliable piece 18 to the wrapping sheet 8 by means of intermediately-spaced transversely extending lines of stitching 19, the edges of the pliable piece 18, where they correspond with the edges 90 of the section, being suitably secured by the binding strip 9. In order to accommodate articles of silverware of different lengths, certain of the pockets on each of the sections may be made of less extent from their open ends 17; this being accomplished by connecting the pliable piece 18 to the wrapping sheet 8 by stitching 20 at the point where the bottom of the pocket is to be located.

By preference, the short pockets on one section may be produced directly opposite the long pockets on the other section as clearly shown in Fig. 1.

In the use of my improved container, the section 13 is folded over and upon the section 12 and along the folding line 11 so as to produce a book-fold; and in this connection it will be observed that I preferably provide a pliable partition 21 arranged to come between the book-folded sections, this partition preferably being secured at one edge on the folding line 11 so as to prevent

the articles of silverware arranged in one series of pockets from coming into contact with the articles arranged in the opposite series of pockets. The book-folded sections, 5 as illustrated in Fig. 2, may be folded transversely to produce superposed layers with the flap 14 extending over the backing sheet 7 as shown, there being secured to the edge 10 of the flap 14 suitable tying tapes 22 and 23 whereby to tie and secure the container in its folded compact form.

While I have illustrated and described the preferred form of construction for carrying my invention into effect, this is 15 capable of variation and modification without departing from the spirit of the invention. I, therefore, do not wish to be limited to the precise details of construction set forth, but desire to avail myself of such variations and 20 modifications as come within the scope of the appended claim.

Having described my invention what I claim as new and desire to secure by Letters Patent is:

25 A container for silverware comprising two pliable sheets consisting of a backing sheet and a wrapping sheet having the same out-

line and area and sewed together along their marginal edges and foldable along a folding line to provide right and left-hand sections; 30 a holding sheet on each section having one marginal edge corresponding with and sewed to the marginal edge of the backing and wrapping sheets and extending over the wrapping sheet a given distance but terminating short of the folding line; intervally spaced lines of stitching connecting the wrapping sheet and holding sheets and defining a series of elongated spaces bounded by the walls of the wrapping sheet and holding sheets; a pliable covering attached to the wrapping sheet and placeable to provide a partition between the wrapping and holding sheets of the right and left-hand sections; 35 extending portions extending from said backing and wrapping sheets at one end of one section and adapted to overlie the backing sheet when the sections are folded; and tie members extending from the extending portions for securing the sections in 40 folded condition, substantially as described.

In testimony whereof I have signed my name to this specification.

FELIX STERNTHAL.
